UNITED STATES PATENT OFFICE.

ROBERT P. RAMSEY, OF DULUTH, MINNESOTA, ASSIGNOR TO CLYDE IRON WORKS, OF DULUTH, MINNESOTA, A CORPORATION OF MAINE.

CABLE BLOCK.

Application filed August 29, 1924. Serial No. 734,932.

The present improvements, relating, as indicated, to cable blocks, have more particular regard to cable blocks of the type that forms the subject-matter of U. S. Patent No. 5 1,243,847 to J. R. McGiffert, dated October 23, 1917. As in the case of such patented block, the object of the present invention is to provide means for enclosing the arms of the frame or housing in which the pulley is 10 mounted in order to effectively brace the same and prevent accidental dislodgement of a cable passing over such pulley. A further object is to provide in such block a thrust or wearing washer, one on each side of the pulley, which may be readily removed for the 15 purpose of replacement when worn and thus avoid the necessity of discarding the entire block.

To the accomplishment of the foregoing and related ends, the invention, then, consists of the means hereinafter fully described and particularly pointed out in the claim, the annexed drawing and the following description setting forth in detail certain mechanism embodying the invention, such disclosed means constituting, however, but one of various mechanical forms in which the principle of the invention may be used.

In said annexed drawing:—

30 Fig. 1 is a side elevation of my improved cable block; Fig. 2 is an end elevation with one side shown in vertical central section, as indicated by the line 2—2, Fig. 1; and Fig. 3 is a perspective view of the aforesaid thrust or wearing washer that forms one of the features of improvement.

The frame of the block is in general of familiar design, comprising two side members 1 and 2, in the respective lower ends 40 of which is fixedly secured the transverse spindle 3 upon which the pulley or sheave 4 is rotatably mounted.

Pivots secured to the upper end of the arm 1 of said frame is a clevis 5 that constitutes one of the features of improvement herein. This clevis is of the usual semi-circular or U shape and when closed is secured in place by means of a removable pin 6 that passes through its other end and the upper end of frame member 2. The latter, it will be noted, is formed on its inner face with an outwardly inclining or beveled surface 7. The end of the clevis that is pivotally attached to frame member 1 has formed inte-

grally therewith an angularly related extension or arm 8 which is adapted to project across the space between the two side members of the frame and has its extremity 9 of complementary form to the surface 7 on said side frame member 2. The rear face 10 of extension 8 is inclined in the opposite direction to its extremity 9, the two inclined surfaces being symmetrical with the center line of the block, and side frame member 1 is provided with a bearing face 11 identical 55 with face 7 on member 2. In fact, the two side frame members are identical throughout, being made from the same pattern or die so as to constitute interchangeable parts in the assembly of the block.

As shown in dotted outline in Fig. 2, when pin 6 is withdrawn, the clevis may be turned back on its pivotal bearing in side frame member 1 so as to leave the throat of the block entirely clear of any projecting part 75 when it is desired to place a cable in the block or remove such cable therefrom. In other words, it is unnecessary to thread such cable or line through the throat of the block. However, when the clevis is secured in its closed position, the arm 8 constitutes an effective line guard and prevents such cable from running up into the curved part of the clevis. The arm furthermore bears against both sides of the block, the bearing faces 7 85 and 11 of the two side frame members being identical and the contacting portions of the arm being complementary, as hereinbefore explained. The semi-circular clevis is thus prevented from closing up under heavy 90 load and at the same time the tops of the block-sides are prevented from bending together.

Ordinarily in blocks of the kind in hand, the frame parts are made of open hearth 95 steel, while the pulley or sheave is made of manganese steel because of its longer wearing quality. The result, however, is that the inner faces of the side frame members 1 and 2 that contact with the ends of the hub of the pulley wear away more rapidly than such hub ends. To increase the life of the block, I accordingly insert in each side member a thrust or wearing washer 12 of manganese steel just like the sheave, such washer bearing against the opposed hub end 13 of the sheave. Such washer is formed with two oppositely located pins or dowels

14 that are adapted to enter corresponding apertures or recesses 15 in the inner face of each side frame member. Said dowels are of such length that even though the washers 5 be worn thin and corresponding side play be permitted the sheave on spindle 3, the washers nevertheless cannot back loose from the holes 15 and so revolve with the sheave.

It will be understood that these washers 10 need not necessarily be of the same material as the sheave, but may be made of any material suited to the bearing duty they have to perform. As clearly shown in Fig. 2, the washer is somewhat wider than the opposed 15 hub face so that all the wear is sustained by the latter and such washer.

Other modes of applying the principle of my invention may be employed instead of the one explained, change being made as regards the mechanism herein disclosed, provided the means stated by the following 20 claim or the equivalent of such stated means be employed.

I therefore particularly point out and distinctly claim as my invention:—

In a cable block, the combination of a frame comprising two side members, the latter being duplicates, a pulley mounted between said side members, a clevis pivotally attached at one end to one of said side members, and an angularly related arm on said clevis adjacent such pivotally attached end adapted to extend entirely across the space between said side members, such space being left clear when said clevis is swung upwardly about its axis, said side members having upwardly and outwardly inclining faces symmetrically disposed with the center line of the block and said arm being formed with faces complementary to those on said side members and adapted to contact therewith in the closed position of said clevis.

Signed by me this 23rd day of August, 1924.

ROBERT P. RAMSEY.
